UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Original application filed June 15, 1922, Serial No. 563,525, now Patent No. 1,584,482, issued May 11, 1926.
Divided and this application filed July 5, 1923. Serial No. 649,514.

This invention relates to an uncoupling device known in the art as the push down type or vertical plane type wherein the levers are fulcrumed upon the end sill of the car, having their inner end operatively connected to the eye of the lock lifter and having the outer end positioned relative to the car so as to be operated by the hand or the foot of the switchman. The levers, therefore, move in substantially a vertical plane so that a pressure by hand or foot on the outer end of the outer lever raises the inner end of the inner lever which, being connected with the lock lift of the coupler, unlocks the coupler and automatically throws the knuckle. The invention, however, does not relate to parts or actions of the coupler.

An object of this invention is to increase the bearing area of the operating lever upon the fulcrum, thus reducing the friction, and furthermore, to prevent its tipping and wabbling which cause friction.

Another object is to prevent this same wabbling and tipping of the pin lifting lever, at the same time allowing the pin lifting lever to swing laterally from its junction with the fulcrum to accommodate itself to the fore and aft movement of the coupler without transmitting any lateral movement to the operating lever.

Another object is to obtain a light and very strong operating lever, yet very simple to make.

The stop to limit the rotative movement of either of the two levers in a vertical plane may be provided in any convenient manner, for instance, it may be cast integral with the fulcrum.

It will be noted that the two levers, the fulcrum and the fulcrum bracket, are all very simple to make or repair and can be assembled by an unskilled person and cannot be improperly applied.

In the drawings:

Fig. 1 is a fragmentary elevation of a freight car with the device applied thereon.

Fig. 2 shows an enlarged plan view of the fulcrum and the fulcrum ends of the two levers.

Fig. 3 is an elevation of Fig. 2.

Fig. 4 shows the fulcrum end of the operating lever.

Fig. 5 shows the fulcrum end of the pin lifting lever:

Fig. 6 shows side elevation of fulcrum casting.

Fig. 7 shows end elevation of fulcrum casting.

Numeral 1 is the end of the car; 2 is the coupler; 3 is the coupler lock block eye; 4 is the fulcrum with large portion 44 and reduced journal portion 31 forming a shoulder for the operating lever 33.

The operating lever 33 is provided with bifurcations 34 and 35 which have perforations 36 which engage the fulcrum 31. The pin lifting lever 30 has perforation 37 which engages fulcrum 31.

The pin lifting lever 30 extends beyond the fulcrum 31 and is formed in a T head 32, the two bars of which engage the bifurcated end of the operating lever 33 so that a downward movement of the operating lever raises the pin lifting lever; furthermore, the T head engagement between the two levers prevents the pin lifting lever from tipping and causing friction between it and the fulcrum.

The bifurcated end of the operating lever 33 doubles its bearing area on the fulcrum 31 and also prevents it from tipping or wabbling and causing friction between it and the fulcrum. Furthermore, it prevents it from swinging laterally which would make it dangerous for the operator.

The pin lifting lever is positioned on the common fulcrum between the bifurcations of the operating lever, which bifurcations are spaced apart so that the coupler end of the pin lifting lever may move with the coupler in draft without binding, distorting or moving the operating lever. Furthermore, the spacing apart of these bifurcations reduces the tipping tendency of the operating lever.

The fulcrum 31 has key or projection 38 which engages keyways 39 in the ends of operating lever 33 and also engages keyways 40 in pin lifting lever 30. However, keyways 39 and 40 are somewhat larger than key 38 to permit the operating and pin lifting levers to move in a vertical plane a predetermined distance.

The various parts of the device are held

- in operative position by bolts 41 with nuts 42 and washers 43. The fulcrum casting 31 has an enlarged portion 44 which forms a shoulder for the bifurcated end of lever 33. 5 This fulcrum casting is held to the car in any convenient manner, such as by brackets 45.
- This application is a division of my application No. 568,525, filed June 15, 1922.
- 10 I claim:
1. An uncoupling device for car couplers comprising a fulcrum, an operating lever bifurcated at one end to form spaced apart walls having bearings on said fulcrum, and 15 a pin lifting lever mounted on said fulcrum between said walls and extending beyond said fulcrum to have operative engagement with both of said walls.
  2. An uncoupling device for car couplers 20 comprising a fulcrum, an operating lever bifurcated at one end to form spaced apart walls having bearings on said fulcrum and a pin lifting lever mounted on said fulcrum between said walls and extending beyond 25 said fulcrum to engage both of said walls to retain said pin lifting lever in a substantially vertical plane and to operatively engage said levers.
  3. An uncoupling device for car couplers 30 comprising a fulcrum, an operating lever with one end bifurcated to form spaced apart walls having bearings on said fulcrum, and a pin lifting lever mounted on said fulcrum between the said walls, the distance 35 between said walls being greater than the horizontal width of said pin lifting lever whereby the pin lifting lever may move laterally, said pin lifting lever extending beyond said fulcrum to have operative engagement with both of said walls.
  4. An uncoupling device for car couplers 40 comprising a fulcrum, an operating lever with one end bifurcated to form spaced apart walls having bearings on said fulcrum, and a pin lifting lever mounted on said fulcrum between the said walls, the distance 45 between said walls being greater than the horizontal width of said pin lifting lever whereby the pin lifting lever may move laterally, said pin lifting lever extending beyond 50 said fulcrum to have operative engagement with both of said walls, and to retain said pin lifting lever in substantially a vertical plane.
  5. In an uncoupling device for railway cars comprising a fulcrum having a journal provided with a lateral extension, a pin lifting lever perforated for said journal, said perforation contoured so that said extension 55 limits the rotation of said lever about said journal, and an operating lever operatively connected to said pin lifting lever.
  6. In an uncoupling device for railway cars comprising a fulcrum having a journal provided with a lateral extension, an 60
- operating lever, and a pin lifting lever, said levers perforated for said journal and operatively connected together, the perforation in one of said levers contoured so that said extension limits the rotation of said lever 70 about said journal.
7. An uncoupling device for car couplers comprising a fulcrum, a lever bifurcated to provide two portions bearing on said fulcrum, and another lever mounted on said fulcrum between said portions and extending beyond said fulcrum to operatively engage both of said portions. 75
8. An uncoupling device for car couplers comprising a fulcrum, an operating lever bifurcated to provide two portions bearing on said fulcrum, and a pin lifting lever mounted on said fulcrum between said portions, said pin lifting lever extending between said portions and provided with lateral projections to operatively engage both of said portions. 80
9. An uncoupling device for car couplers comprising a lever having an aperture adjacent its fulcrum end, and a fulcrum passing through said aperture; the contour of 90 said aperture and said fulcrum, respectively, arranged to restrict the movement of the lever about the fulcrum.
10. An uncoupling device for car couplers comprising an operating lever having an aperture adjacent its fulcrum end, a pin lifting lever having an aperture adjacent its fulcrum end operatively connected to said operating lever, and a fulcrum passing through 100 said apertures, the contours of said apertures and fulcrum respectively arranged to restrict the movement of said levers about said fulcrum.
11. An uncoupling device for car couplers comprising a fulcrum with an integral stop, a pin lifting lever, and an operating lever each provided with an aperture for engagement with said fulcrum, said levers operatively connected together, one of said apertures formed with an integral shoulder to engage said stop to restrict the movement of 110 said lever about said fulcrum.
12. An uncoupling device for car couplers comprising a fulcrum with an integral stop, a pin lifting lever, and an operating lever each provided with an aperture for engagement with said fulcrum, said levers operatively connected together, each of said apertures formed with integral shoulders to engage said stop to restrict the movement of 120 said levers about said fulcrum.
13. An uncoupling device for car couplers comprising an operating lever having an aperture adjacent its fulcrum end, a pin lifting lever having an aperture adjacent its fulcrum end, and a fulcrum having a journal passing through said apertures, said journal and said apertures so contoured as 125 to restrict the rotative movement of each 130

lever about the journal independent of the other lever, said levers operatively connected together.

14. An uncoupling device for car couplers comprising an operating lever bifurcated at one end to form spaced apart walls with apertures therein, a pin lifting lever positioned between said walls and having an aperture adjacent its fulcrum end, and a fulcrum having a journal passing through said apertures, said journal and said apertures so contoured as to restrict the rotative movement of each lever about the journal independent of the other lever, said levers operatively connected together.

15. An uncoupling device for car couplers

comprising a lever having a key-wayed aperture adjacent its fulcrum end, and a keyed fulcrum passing through said aperture, the key of the fulcrum engaging the keyway 20 of the lever upon a predetermined movement of said lever.

16. An uncoupling device for car couplers comprising an operating lever having a key-wayed aperture adjacent its fulcrum end, 25 a pin lifting lever having a key-wayed aperture adjacent its fulcrum end, and a keyed fulcrum passing through said apertures, the key of said fulcrum restricting the movement of either of said levers by engaging the 30 corresponding keyway.

ARTHUR E. SMALL.
